DESIGN FOR A DECK OF PLAYING CARDS

John Scott Kelly, Detroit, Mich.

Application March 10, 1936, Serial No. 61,551

Term of patent 14 years

To all whom it may concern:

Be it known that I, John Scott Kelly, a citizen of the United States, residing at Detroit, in the county of Wayne and State of Michigan, have invented a new, original, and ornamental Design for a Deck of Playing Cards, of which the following is a specification, reference being had to the accompanying drawing, forming part thereof.

Figures 1, 2, 3, and 4 are face views, the parts in full lines illustrating the design of the four face cards of each suit of the deck of cards showing my new design.

Figure 5 is a face view of the joker, the remaining cards of the deck, as well as the backs of all the cards thereof, being conventional.

The ornamentation upon the faces of these cards is the dominant feature of my design.

I claim:—

The ornamental design for a deck of playing cards, as shown and described.

JOHN SCOTT KELLY.
